UNITED STATES PATENT OFFICE.

ROY G. WHISLER, OF FORT WORTH, TEXAS.

ICE-MAKING APPARATUS.

Application filed July 23, 1925. Serial No. 45,587.

This invention relates to improvements in ice making apparatus and has especial reference to that form of ice making apparatus generally identified in the art as atmospheric tank freezers, the invention having for an object to provide the can holders or cabinets of the apparatus with novel forms of combined guides and catches releasably engageable with the water containing cans whereby to retain the same in properly immersed positions in the brine freezing solution during a process of freezing, being readily disengaged from said cans to permit their removal following freezing of the contents thereof.

It is also an object of the invention to provide a device of the character mentioned including a novel construction and arrangement of frame, the opposite side portions of which serve as effectual forms of guides for those cans being placed in and removed from the can holders or cabinets, said frames being each provided with means for facilitating the arrangement of the same in immovable position adjacent the receiving portions or sides of the can holders or cabinets and also including novelly arranged means for receiving and pivotally supporting the can catch devices.

Yet another and equally important object of the invention is to provide a combined can guide and catch wherein the latter is mounted upon the frame in such a manner as to, with the application of excessive stress or strain thereto, permit its breaking or rupturing from the particular pivotal mounting therefor upon said frame without damage to such frame or to the portions of the can holder or cabinet receiving the frame, hence, permitting ready replacement of the catch without expensive or time-absorbing repairs to any other parts of the apparatus.

Other objects of the invention will be in part obvious, and in part pointed out hereinafter.

In order that the invention and its mode of operation may be readily understood by persons skilled in the art, I have in the accompanying illustrative drawings, and in the detailed following description based thereupon, set out one embodiment of the same.

In these drawings:—

Figure 1 is a fragmentary detail in perspective showing the mode of placement of

the combined can guide and catches in or upon the can holder or cabinet;

Figure 2 is a vertical fragmentary detail in section through portions of the water containing can showing the relative arrangement of the combined can holder guide and catch with respect thereto; and,

Figure 3 is an enlarged detail in perspective of the improved form of combined can guide and catch.

Having more particular reference to the drawings, in connection with which like characters of reference will designate corresponding parts throughout, the improved device may be stated to be particularly advantageous for use in that form of atmospheric tank freezer apparatus wherein bracing timbers or bars indicated herein by the numeral 1 are employed for dividing the upper or mouth portion of the can holder or cabinet into a plurality of individual can receiving compartments, these bracing timbers, in turn, being relatively rigidly interconnected and held in equi-distant spaced relation through the medium of metal or other suitable bars 2 arranged in superposed relationship and paired fashion, as is clearly shown in the Figure 1, those portions of said bars 2 adjacent or intersecting the bracing timbers 1 at the regular intervals being connected to the same through the medium of fastening devices, indicated for the purpose of convenience by the numeral 3. In this connection, it, of course, will be noted that the bars 2 are arranged at substantially right angles with respect to the bracing timbers 1 and thus complete the individual can receiving compartments aforesaid, at the mouth of the can receiving or retaining cabinet. Other divisional bars 4 are arranged intermediately of and parallel to the various bracing timbers 1, in the manner clearly shown in the drawings, and have those portions of the same inter-connecting the intermediate portions of the lower bars 2 rigidly connected thereto through the medium of rivets, screws, bolts, or other fastening devices 5, the lower face sides of each of these divisional bars 4 being preferably faced with a wear resisting or compensating metal stripping or sheathing 6, for obvious purposes. In this connection, it is to be noted that the marginal portions of the sheathing 6 extends for a distance

means against which the opposite sides of a can being introduced into or removed from the cabinet abut. Also, in this connection, it is to be noted that the lower face side or 5 marginal portions of the bracing timbers 1 are provided with similar metal sheathing, indicated for the purpose of convenience herein by the numeral 7, the opposite edges or marginal portions of said casing being 10 disposed with respect to the corresponding faces of the bracing timbers in a manner corresponding to the arrangement described in connection with the divisional bars 4.

By the construction aforesaid, the can 15 holder or cabinet, as stated, is provided with means for dividing the mouth portion thereof into distinct or individual can receiving compartments and in order that these various cans when arranged in such compartments within the cabinet may be properly held in partly immersed positions in the brine freezing solution, the improved can 20 guides and catches, forming the subject of this invention, are provided.

25 The improved can guides and holders may be stated to each comprise cast or otherwise suitably formed metal frames 8, substantially rectangular in configuration and having the upper portions thereof provided with 30 converging or inclined sides 9, the upper extremities of said frame being provided with bolt receiving openings 10, while the lower extremities thereof are provided with lug-like dependent extensions 11, which extensions 35 are arranged in opposed fashion as is clearly shown in the Figures 2 and 3 and are so spaced with respect to each other as to snugly and embracingly engage over the upper face and marginal portions of the lower- 40 most of the superposed pairs of bars 2, providing, after a fashion, forms of channels for the frames whereby the same will be stabilized in their respective positions as between the said bars 2. To anchor these 45 frames 8 in their positions between the superposed bars 2, bolts 12, or other suitable fastening devices are passed through openings formed in the uppermost of said bars 2 and 50 through the bolt receiving openings 10 formed in the upper extremities of said frame 8, whereupon suitable locking devices are turned into engagement with the screw threaded extremities thereof and thus serve to positively and rigidly locate the frames 55 with respect to the individual can receiving compartments of the ice making apparatus.

Because of the straddling engagement of the lower ends of the various frames 8 with the lower bars 2, it will be also understood 60 that the plane surfaces upon the outer sides of said frames 8 will be fixedly positioned with respect to the individual can receiving compartments of the apparatus and therefore, will afford an efficient and practical 65 form of guide means for such cans especially

advantageous during the placing of such cans into or their removal from said individual receiving compartments, the placing of the cans into such compartments being even more facilitated through the provision 70 of the inclined upper side portions 9 of said frames 8.

Each of the rectangular frames 8 are provided with integrally cast or otherwise formed intermediately disposed and horizontally positioned webs 13, having the opposite extremities thereof extended for distances beyond the opposite edge or marginal portions of the opposite sides of said frames 8 as is clearly shown in the Figures 80 1 and 3, portions of these extensions being cut away, as indicated by the numeral 14, for a purpose which will be subsequently described. The spaced positioning of the webs 13 is such as to provide their respective 85 frames 8 with spaced pairs of pivotal bearing plates, which are indicated herein for the purpose of convenience by the numeral 13', the outer extremities of such extensions being formed with vertically aligned bearing 90 openings. Horizontally swingable catches or can holders proper designated by the numeral 15 are provided the frames 8 and are preferably formed of some soft material, such as brass or the like, whose tensile 95 strength is less than that of the material from which the integrally formed webs 13 are constructed. Also, if desired, these catches may be further weakened by cutting away portions of the under sides thereof, as 100 indicated at 16 so that their degree of stress resistance will be decidedly less than that of the extensions 13' of said webs 13. Each of these catches 15 are provided with sleeve-like bearings 17 upon their inner ends, the 105 lengths of which are such as to permit their snug reception between the extensions 13' in the manner shown in the Figures 2 and 3, whereupon vertically disposed pivot pins 18 are passed therethrough and have their 110 opposite ends anchored in the bearing openings heretofore described. Thus, it will be understood that limited horizontal swinging movement of the catches 15 will be permitted.

115 Each of the frames 8 are provided with two of these horizontally swingable catches 15, the same being arranged between and adjacent the extensions 13' formed upon the opposite ends of the webs 13 and hence, it 120 will be understood that each of said frames will be provided with means for engaging and retaining two juxtaposed water receiving or containing cans in properly immersed 125 positions within the can holder or cabinet of the ice making apparatus.

130 From the foregoing, it will be understood that by my improved form of combined can guide and catch, I am enabled to releasably secure water containing cans in properly im-

mersed positions within the can receiving compartments of a holder or cabinet of ice making apparatus, such cans being arranged in juxtaposed relationship in their various individual compartments as afforded by the timbers and bars 1, 2, and 4, hereinbefore described. To engage the catches 15 with the adjacent marginal portions of the cans, such as indicated herein by the numeral 19, it is only necessary that the free portions of the adjacent catches 15 be engaged and swung to positions in substantial parallelism to the plane outer surfaces of the opposite sides of the various frames 8, whereupon said catches will have that form of engagement with the adjacent marginal portions of the cans 19 as clearly shown in the Figure 2. With the cans 19 so engaged, it will be understood that they will be retained in properly immersed positions in the brine freezing solution within the cabinet or holder of the ice making apparatus and hence, that a process of freezing may be then efficiently performed. When, however, it is desired to remove the cans 19 from the brine freezing solution, the catches 15 may be then engaged and swung to positions at substantial right angles to the plane outer surfaces of the opposite sides of the frame 8, for example, as is shown in the Figure 3, causing said catches to be disengaged from the adjacent marginal portions of the cans 19 and then permitting said cans to be floated in the brine solution and removed from the ice making apparatus as desired.

It often times occurs in the manufacture of ice that workers in hasty and thoughtless moments neglect to disengage the various catches 15 from the various water or ice containing cans 19 and with the following removal of said cans from the apparatus, break or rupture the catches. In this connection, it is to be noted with particularity, that because of the construction of the various catches 15, when excessive stress or strain is exerted thereupon, the same will break without doing damage to their pivotal mountings in their respective frames 8; this being because of the fact, as heretofore noted, that the degree of resistance qualities is less than that of their pivotal mountings, to-wit, the pivot pins and the extensions 13' of the webs 13. Consequent upon this, it will be understood that the broken or ruptured catches 15 may be quickly and readily replaced merely by removing their particular pivot pins 18 and then placing new catches between the extensions 13', then reengaging the pivot pins 18 with the latter. In absence of damaging of the extensions 13', the webs 13 or the pivot pins 18, it, of course, will be understood that the cost of repair will be kept at minimum and also, that the time and effort consumed by such a repairing operation will be likewise minimized

to the material advantage and saving of an employer or manufacturer.

It is to be also noted that because of the straddling engagement of the lower ends of the various frames 8 with the lowermost bars 2, brought about by the forming of the spaced dependent lugs 11 thereupon, that the opposite sides of the frame 8 will be fixedly positioned with respect to the can receiving compartments in which the same are arranged. Thus, the plane outer surfaces of the opposite sides of said frame 8 will serve as highly efficient and advantageous forms of guides for the water and ice containing cans, both during their introduction into the ice making apparatus and their removal from the same subsequently to a freezing process. Furthermore, by reason of the formation of inclined sides 9 upon the upper extremities of the opposite sides of said frames 8, the introduction or placement of water containing cans in the various individual compartments of the can holder or cabinet of the apparatus may be materially facilitated, since these inclined sides will serve to center or properly position the water containing cans with respect to such individual compartments during their engagement and lowering into the apparatus.

By cutting away portions of the extensions 13' as indicated herein by the numeral 14, means are also afforded whereby positive and convenient access may be had to the horizontally swingable catches 15 at all times.

Manifestly, the construction shown is capable of considerable modification, and such modification as is within the scope of my claims, I consider within the spirit of my invention.

I claim:—

1. A device of the character described comprising a frame, bearing means on said frame of a predetermined stress resisting quality, and catches movably mounted upon said bearing means, said catches possessing stress resisting qualities of a lesser degree than those of said bearing means.

2. A device of the character described comprising a frame, oppositely disposed bearing means on said frame of a predetermined stress resisting quality, and catches movably mounted upon said opposed bearing means, said catches possessing wear resisting qualities of a degree less than those of the bearing means.

3. A device of the character described comprising a frame, bearing means on said frame of a predetermined stress resisting quality, and catches pivotally mounted upon said bearing means, said catches possessing stress resisting qualities of a lesser degree than those of said bearing means.

4. A device of the character described comprising a frame having oppositely dis-

posed bearing means formed integral therewith, said bearing means being of a predetermined stress resisting quality, and catches pivoted to each of said bearing means, said catches possessing stress resisting qualities of a lesser degree than those of said bearing means.

5. A device of the character described comprising a frame, webs formed integral with the intermediate portions of said frame and arranged in spaced relation, the opposite extremities of said webs being extended, said webs and their extensions possessing a predetermined stress resisting quality, and catches pivotally mounted between the extensions of said webs, said catches possessing stress resisting qualities of a lesser degree than those of the webs and their extensions.

6. A device of the character described comprising a frame, pairs of horizontally positioned relatively spaced webs formed integral with the intermediate portions of said frame, each of the opposite ends of said webs being extended beyond the adjacent edges of the frame, said webs and their extensions possessing a predetermined stress resisting quality, and catches pivoted for horizontal swinging movement between the extensions of said webs, said catches each possessing stress resisting qualities of a lesser degree than those of said webs and their extensions.

7. A device of the character described comprising an elongated frame having the outer surfaces of the opposite sides thereof formed plane, bearing means on said frame of a predetermined stress resisting quality, and catch means movably mounted upon said bearing means, said catch means possessing stress resisting qualities of lesser degree than those of said bearing means.

8. A device of the character described comprising an elongated substantially rectangular frame, saddle means formed upon the lower end of said frame, bearing means on said frame of a predetermined stress resisting quality, and horizontally swingable catches pivoted upon said bearing means, said catches possessing stress resisting qualities of a lesser degree than those of the bearing means.

9. A device of the character described comprising a substantially rectangular frame, the opposite sides of said frame being formed with plane outer surfaces,

saddle means formed upon the lower end of said frame, the upper portion of the sides of said frame being inclined, bearing means on the frame possessing a predetermined stress resisting quality, and horizontally swingable catches pivoted upon said bearing means, said catches possessing stress resisting qualities of a lesser degree than those of said bearing means.

10. A device of the character described comprising a substantially rectangular frame having the upper portion thereof constricted, the outer faces of the opposite sides of said frame being plane, saddle means formed upon the lower end of said frame, pairs of horizontally positioned webs integral with the intermediate portion of said frame and arranged in spaced relation, each of said webs having extensions formed upon their opposite ends, said webs and extensions possessing a predetermined stress resisting quality, and horizontally swingable catches pivotally mounted between the extensions of said webs, each of said catches possessing stress resisting qualities of a lesser degree than those of said webs and their extensions.

11. A device of the character described comprising a substantially rectangular frame having the upper portion of the opposite sides thereof converging, the outer surfaces of said opposite sides being plane and the upper extremities of said frame having a fastening device receiving opening therein, dependent lugs formed upon the lower end of said frame, spaced horizontally positioned webs rigidly positioned adjacent the intermediate portion of said frame having opposed extensions, said extensions being extended to points beyond the adjacent marginal portions of said frame, said webs and their extensions possessing a predetermined stress resisting quality, and horizontally swingable catches pivoted between said extensions, said catches possessing stress resisting qualities of a lesser degree than those of said webs and their respective extensions.

12. A device of the character described comprising a frame, spaced bearings on said frame and catches movably mounted between said bearings and having a lesser degree of stress resisting quality than the latter.

In witness whereof I have hereunto set my hand.

ROY G. WHISLER.
